The ornamental design for an interconnectible storage unit, as shown and described.

DESCRIPTION

FIG. 1 is a perspective view of an interconnectible storage unit showing my new design;

FIG. 2 is a perspective view with the door in open position;

FIG. 3 is a top plan view thereof;

FIG. 4 is a front elevational view thereof;

FIG. 5 is a right side elevational view thereof;

FIG. 6 is a bottom plan view thereof;

FIG. 7 is a top plan view of a second embodiment of the interconnectible storage unit shown in FIG. 1 thereof; and, FIG. 8 is a top plan view of a third embodiment of the interconnectible storage unit shown in FIG. 1.

The broken lines showing of other units in FIGS. 3, 7, and 8 are for illustrative purposes only and form no part of the claimed design.
